UNITED STATES PATENT OFFICE

2,421,464

SCAFFOLD CASTER

Leo A. Reiner, Detroit, Mich.

Original application April 30, 1942, Serial No. 441,080, now Patent No. 2,359,583, dated October 3, 1944. Divided and this application February 18, 1944, Serial No. 522,909

2 Claims. (Cl. 16—35)

1

The present invention relates to scaffolds, and more particularly to scaffolds formed of detachable units, with casters on the lowermost scaffold unit. This application is a division of my copending application Serial No. 441,080, filed April 30, 1942, now Patent No. 2,359,583, dated October 3, 1944.

The primary object of the invention is to provide a scaffold of the above-mentioned type with a caster for the lower scaffold unit to facilitate the easy transportation of the scaffold in its assembled form to various locations.

Another object of the invention is to provide a scaffold structure formed of a series of units demountably connected which units are constructed of tubular material so that the joints may be easily assembled during erection in a minimum amount of time.

Another object of the invention is to provide a scaffold of the under pass type to allow for the passage of workmen and building construction materials by arranging the units in spaced relation and connecting the units by detachable truss rods.

Another object of the invention is to provide a scaffold formed of a series of spaced units held in position by truss rods which have their ends detachably connected to threaded studs welded to the units by securing a double ended threaded member to the threaded stud so that the threaded member may be reversed if desired to provide a relatively long and short stud member for receiving the truss rods.

Another object of the invention is to provide a demountable sectional scaffold having caster supports which may be locked against movement by brake devices so that the swinging movement of the caster relative to the sectional unit may be prevented as well as the caster itself.

Other objects and advantages will become apparent during the course of the following description of the accompanying drawings, wherein:

Figure 1 is a side elevational view of the scaffold unit embodying the invention, of the underpass type, illustrating the manner in which the casters are arranged on the lowermost scaffold unit;

Figure 2 is a front elevation of the same showing the manner in which the units are separably connected and further illustrating the caster members affixed to one of the vertical standards of the scaffold;

Figure 3 is a top plan view of the caster support for being attached to the lower ends of the scaffold unit shown in Figures 1 and 2, illustrating

2

the brake lock for preventing rotational movement of the caster; and

Figure 4 is a side elevation partly in section illustrating the caster brake and the manual operator therefor.

In the drawings, wherein for the purpose of illustrating the invention like reference characters will be employed to designate like parts throughout, the reference character 10 will generally be employed to designate a scaffold unit including vertical standards 11 connected at the top by a horizontal bar 12 the ends of which are provided with sleeves 13 for receiving a portion of the free upper end of the vertical standard 11. The horizontal bar 12 is welded or otherwise secured at its ends to the sleeves 13 and a parallel base bar 14 likewise has its ends connected to tubular stock 15 welded to the sleeves 13 as clearly shown in Figure 1. Brace bars 16 have their lower ends bevelled for being attached as by means of welding to the vertical standards 11 and have their upper ends welded as at 17 to the juncture of the tubular brace bars 14 and 15. An intermediate brace 18 supports the horizontal bars and holds them in spaced relation.

Each of the units above described is preferably formed of tubular stock welded at the joints to provide a relatively rigid frame unit capable of supporting excessive weight and load as well as stresses and strains. It is intended to provide a series of such units arranged in superposed side by side relation for being connected in parallelism by means of diagonal truss rods 19 and horizontal connecting rods 20 (Figure 2). The free ends 30 of the truss rods 19 and 20 are detachably connected to studs 21 including a threaded member as shown in Figure 1 welded or otherwise secured to the vertical standards 11 adjacent the ends thereof, there being one stud 21 provided for the

40 lower end of each diagonal truss bar and a threaded stud member for attachment with the upper ends of the diagonal truss bars as well as the ends of the horizontal bars 20. Each stud member 21 is threaded as at 22 for receiving a double ended bolt 23 having a relatively shortened end 24 and an opposed end 25 of a greater length so that the double ended bolt 23 may be reversed depending upon whether the bolt is used for anchoring the lower ends of the truss rods 50 or the upper ends, in which case it would be necessary to employ the threaded portion of the nut having a greater length as at 25. After the ends of the truss rods 19 have been placed upon the double ended bolt, a wing nut 26 is threaded thereon to securely hold the truss rods in posi-

tion. The free ends of the truss rods 19 and 20 are flattened as at 27 to facilitate the easy attachment of said ends to the double ended bolt.

It is to be noted that the tubular connecting elements 13 extend well above the horizontal connecting bar 12 as at 28 for receiving the lower end of a superposed unit as shown in Figures 1 and 2. It is proposed to construct each scaffold unit 10 so that the connecting sleeves 28 will receive the lower end of a superposed scaffold unit and thereby support the same so that the units may be quickly and easily demounted or assembled at different locations of construction.

A runway formed of planking 30 may be supported by the horizontal connecting bars 12 and an additional runway portion or support may be provided and comprises a triangular frame unit including a horizontal bar 31 connected to a vertical supporting bar 32 by being welded or the like thereto as at 33. A brace bar 34 has its lower end connected to the vertical bar as at 35 by welding or the like while the upper end is connected to the horizontal bar 31 by means of a weld joint 36. The extreme free end of the brace bar 34 is extended as at 37 to provide a limiting stop for additional planking or runway boards 38 supported by the horizontal bar 31. The upper and lower portions of the vertical bar 32 are provided with brackets 39 and 40 for gripping one of the vertical standards 10. A complementary strap portion 44 has one of its ends as at 45 keyed in a slot in the bracket 39 while its opposite end terminates in a strap portion 46 complementary with the strap portion 42. A depending horizontal connecting bar and bracing portion 47 depends from the strap portion 46 and a bolt 48 is provided for clamping the parts 41 and 42 about the sleeve 13 while the depending portions 43 and 47 embrace the end of the horizontal connecting bar 12.

The lower bracket 40 is formed with a strap portion similar to the strap portion 41 and a clamping strap 49 is keyed therein and is anchored to the free end of the bracket strap by means of a bolt or the like as at 50.

Certain scaffold units are provided with ladders generally designated as at 51 and said ladders include stiles 52 connected by a series of spaced rounds 53. Each ladder unit 51 is of substantially the same length as the scaffold unit so that when the scaffold units are coupled in superposed relation the ladder units 51 will be coextensively arranged. The ladders are attached to the scaffold units by means of horizontal bars 54 carrying intermediate brackets 55 provided with collars 56 for being telescopically received on the upper ends 28 of the sleeves 13. The collars 56 are slightly larger in diameter than their corresponding sleeves so that the collars will fit snugly thereon. The lower end of each ladder unit carries a pair of spaced horizontal bars 58 to which is attached a bracket 59 having an arcuately curved clamping strap 60 to which is attached a cooperating clamping strap 61 keyed thereto as at 62. The free ends of the clamping straps 60 and 61 as at 62 and 63 respectively are drawn together by means of a bolt 64 so that the lower end of the ladder unit will be supported in a rigid manner and will be prevented from rotation about the axis of the vertical standards 11.

It is intended to provide each leg of the lower scaffold units 10 with swinging casters 64 and said casters are each provided with a casing 66 having a tubular extension 67 for receiving the

lower ends of the vertical standards 11. There being two caster units provided for each scaffold unit and since all of said casters are identical only one will be described in detail. By reference to Figures 3 and 4 wherein is shown one of the casters in detail, it is to be noted that the tubular extension 67 is provided with a central bore 68 for receiving an internally threaded boss 69 formed integral with the housing 66. The lower portion of the tubular extension 67 is annularly flanged as at 70 and is provided with a series of notches or the like 71 for receiving a locking element which will be hereinafter more fully described. A recess 71a is formed in the underface of the annular flange 70 and is adapted to receive a ball race 72 so that the tubular extension 67 may be supported on anti-friction bearings 73 rolling in a ball race 74 received in a recess 75 of the casing 66. An anchoring bolt 76 is threaded in the internally threaded boss 69 and the head thereof as at 77 abuts a washer 78 which overlies the floor of the tubular extension to prevent displacement and separation thereof from the casing 66. The casing is provided with a relatively flat top wall 79 on which is positioned a cam 80 secured in place by means of a bolt 81 extending through the eccentrically formed opening 82 in the cam so that rotation thereof by means of a manual operating lever 83 will move the lever 84 toward and away from the annular flange 70. The locking lever 84 is pivoted to the relatively flat wall 79 as at 85 so that the free end will be interposed between the cam 80 and the annular flange 70. A bolt portion 86 is formed on the free end of the pivoted lever 84 and is curved to fit the contour of the notches 71 in the annular flange 70.

A boot 87 is formed on the housing 66 and is provided with oppositely disposed bearings 88 for receiving a stub axle 89 upon which is rotatably mounted a caster wheel 90. The rear portion of the boot 87 is offset as at 91 so that a shaft 92 may have its free ends journaled in the side walls of the boot. A brake element 93 is pivotally carried by the shaft 92 by means of a bearing portion 94 and formed integral with the bearing portion 94 is an operating arm or extension 95 located in the path of a cam 96 likewise mounted on a shaft 97 journaled in the side walls of the boot 87. An operating lever 98 has its inner end provided with a collar 99 for being attached to the shaft 97 and a stop pin 100 projects from the side wall of the boot 87 to limit the movement of the operating lever 98 in one direction while a similar stop pin 101 mounted opposite the stop pin 100 limits the swinging movement of the brake operating lever 98 in the other direction. A coil spring 102 has one of its ends abutting the brake block 93 while the opposite end is received in a cavity formed in a screw threaded plug 103 threaded in a suitable opening 104 in the offset portion of the boot 91. A lock nut 105 is threaded on the plug 103 so that the plug may be adjusted to increase or decrease tension on the coil spring 102 and then lock in position by the lock nut 105.

It is to be understood that the form of the invention herewith shown and described is to be taken as a preferred embodiment of the same and that various changes may be made in the shape, size and arrangement of parts without departing from the spirit of the invention or the scope of the subjoined claims.

What I claim is:

1. A caster, comprising a caster housing hav-

ing side walls connected by end and top wall portions, a caster wheel axle extending between the side walls, a caster wheel rotatably mounted on said axle with a portion thereof received in said housing, a shaft extending between said side walls, a brake lever pivotally mounted on said shaft, a brake formed on one end of said lever for engaging the peripheral surface of the caster wheel, a rock shaft arranged in spaced parallel relation to said first-mentioned shaft and journaled in the side walls of said caster housing with one end projecting beyond one of said side walls, a cam disc eccentrically mounted on said rock shaft and secured thereto to turn with said shaft, said cam disc being arranged for engaging the opposed end of said brake lever, a manual control lever affixed to said rock shaft to rotate said shaft and thereby move said brake shoe away from said caster wheel, a coil spring interposed between said wall portion and brake shoe for yieldingly urging said brake shoe into frictional engagement with the peripheral surface of said casting wheel, and a screw threaded plug threaded in an opening in said connecting wall portion having a recess in its inner end for receiving one end of said coil spring, the other end of said coil spring being arranged in abutting relation with the brake shoe whereby adjustment of said screw-threaded plug will increase or decrease the yielding pressure on said brake shoe.

2. A caster, comprising a caster housing having side walls connected by end and top wall portions, a caster wheel axle extending between the side walls, a caster wheel rotatably mounted on said axle with a portion thereof received in said housing, a shaft extending between said side walls, a brake lever pivotally mounted on said shaft, a brake formed on one end of said lever for engaging the peripheral surface of the caster wheel, a rock shaft arranged in spaced parallel relation to said first-mentioned shaft and journaled in the side walls of said caster housing with one end projecting beyond one of said side walls, a cam disc eccentrically mounted on said rock

20
15

shaft and secured thereto to turn with said shaft, said cam disc being arranged for engaging the opposed end of said brake lever, a manual control lever affixed to said rock shaft to rotate said shaft and thereby move said brake shoe away from said caster wheel, a coil spring interposed between said wall portion and brake shoe for yieldingly urging said brake shoe into frictional engagement with the peripheral surface of said casting wheel, and a screw threaded plug threaded in an opening in said connecting wall portion having a recess in its inner end for receiving one end of said coil spring, the other end of said coil spring being arranged in abutting relation with the brake shoe whereby adjustment of said screw-threaded plug will increase or decrease the yielding pressure on said brake shoe.
